UNITED STATES PATENT OFFICE.

EARL G. PERKINS, OF YOUNGSTOWN, OHIO.

RHEOSTAT.

Application filed November 26, 1921. Serial No. 517,974.

To all whom it may concern:

Be it known that I, EARL G. PERKINS, a citizen of the United States, residing at Youngstown, in the county of Mahoning and State of Ohio, have invented certain new and useful Improvements in Rheostats, of which the following is a specification.

This invention relates to an improvement in rheostats.

10 A primary object of the invention is to provide a rheostat having two relatively independent resistance units, each adapted to be connected with certain parts of an electrical translating device in such manner that 15 after the current has been supplied to one part of the device to the maximum extent afforded by one unit, the second unit may be brought into use to thereby permit additional amperage to flow to the apparatus 20 in progressively increasing amounts while the maximum amperage controlled by the first unit is maintained in series with the apparatus without variation. That is to say, it is proposed to provide a rheostat 25 having a plurality of resistance units so connected to a translating device, such for instance as an arc lamp, that after the maximum amperage to the lamp has been admitted through one unit, the controller of the 30 rheostat may be so set or adjusted as to augment, progressively and uniformly, the amperage to the lamp over and above the maximum permitted by the first unit to thereby increase the illuminating power of 35 the lamp with due safety to all parts of the apparatus. Thus, a principal object of the invention is to provide in a novel rheostat construction, two distinct power ranges, each controlling a certain part of an electrical device yet both acting in unison, after a 40 maximum has been reached in one power range, thereby rendering the apparatus effectively available as a current controlling and regulating means for any electrical devices, such as arc lamps requiring such regulation.

45 A further object is to provide a simple and practical arrangement of the resistance units which facilitates their manipulation in the manner to produce the desired results.

With the above and other objects in view which will more readily appear as the nature of the invention is better understood, the same consists in the novel construction, combination and arrangement of parts, here-

inafter more fully described, illustrated and claimed.

A preferred and practical embodiment of the invention is shown in the accompanying drawings in which,

60 Figure 1 is a side elevation of my improved rheostat,

Figure 2 is a top plan view thereof,

Figure 3 is a front elevation,

65 Figure 4 is a rear elevation,

Figure 5 is a vertical sectional view taken on the line 5—5 of Figure 1,

Figure 6 is a diagram of the wiring and circuit connections.

70 Similar reference numerals designate corresponding parts throughout the several figures of the drawings.

In carrying the invention into effect the instrumentalities involved for producing the desired electrical result may assume various 75 forms and the details of arrangement may be also varied, but a simple and practical embodiment is illustrated in the accompanying drawings from which it will be observed that the improved rheostat includes the 80 front and rear frame members 1 and 2 which may be connected by a platform or floor member 3 to thereby provide a support for the resistance units R and R', hereinafter referred to as the primary and secondary 85 resistance units respectively and carried by the removable frame F.

In connection with the resistance units R and R' above mentioned, it will be observed that the said units are oppositely arranged 90 within the frame F and each consists of a pair of insulating supporting spools α arranged in parallel relation and having wound thereon the resistance element which consists of a single length of wire formed 95 into two coils respectively carried on the separate spools of the said pair. In that way a wire of considerable length may be utilized to permit of an increased range of resistance obtainable from the wire.

100 The members 1 and 2 may be provided with the insulating terminal walls 4 and 5, the former having mounted thereon a controller C and the latter carrying the line wire terminals P and N respectively for the 105 positive and negative line wires L, or the two poles of the line wires, if alternating current is used. In addition to the line wire terminals P and N, the rear insulating terminal wall 5 also carries the binding ter- 110

minals 6, 7 and 8, which, as will be observed from Figure 6, may be connected with a translating device, such for instance as a solenoid-controlled arc lamp A.

5 The controller C essentially consists of the handle 9 for manipulating the contact arm 10 over a series of contact members or buttons 11, 12, 13, 14, 15 and 16 which are electrically connected to the coil winding p 10 of the primary resistance unit R at spaced intervals by the wire connections 11^a, 12^a, 13^a, 14^a, 15^a and 16^a and the looped terminal bands T or their equivalent, as clearly shown in Figures 1 and 2 of the drawings.

15 In addition to the buttons referred to for the primary resistance unit R the controller also includes an insulating segment 11' and a series of contact buttons 12', 13', 14', 15' and 16' which are electrically connected by 20 the wires 12^b, 13^b, 14^b, 15^b and 16^b with the coil s of the secondary or shunt resistance unit R'. As in the case of the primary resistance unit the connections between the buttons 12'-16' and the coil s are arranged 25 at spaced intervals and are connected with the coil by the terminal bands or loops T'.

It will thus be apparent that when the controller handle 9 is moved to shift the arm 10 in the direction of the arrow (Figure 6), 30 the arm will contact successively with the buttons 11 to 15, inclusive, while its opposite end is swinging over the dead segment 11', and when one end of the arm 10 engages with the segmental contact 16 the opposite 35 end will engage with the button 12' of the set of contacts belonging to the secondary resistance unit R'. Upon the further shifting of the arm the same will engage the contacts 13'-16' in succession while the opposite 40 end is still contacting with the segment 16 of the contacts for the primary resistance unit R.

Referring further to Figure 6 of the drawings, it will be observed that the contact arm 45 10 is electrically connected through the wire 10^a directly to the terminal P of the main power line, while the other terminal N of the power line is connected with the binding post 8 by the wire connection 8^a, and the 50 said binding post 8 is in turn directly connected with one of the carbons of the arc lamp A. It will be therefore apparent that the current divides at the rheostat, one pole or side going through the resistance units 55 thereof while the opposite pole or side goes direct to the arc lamp or other translating device.

In the particular example illustrated in the present case, the arc lamp A is the translating device which may be the electrical device to be controlled by the rheostat. This arc lamp may be of the type used in photographic work and includes the usual solenoid and armature element B. In this well-known type of lamp the current passes

through the solenoid, causing the armature to be drawn into the solenoid under the magnetic influence of the same, and the armature in turn is directly or indirectly connected with the carbons of the arc so that 70 any movement of the armature toward the solenoid will cause the carbons of the arc to separate.

In the arrangement shown therefore, the carbons of the arc lamp A and the solenoid 75 B are included in series with the primary resistance unit R, and to that end the primary coil p of that unit may be connected by the wire p' with the terminal 6 of the rheostat, and said terminal is in turn connected through the wire p² with the solenoid, the latter having connection p³ with one of the carbons of the arc lamp A.

In the operation of the rheostat, it will be apparent that the primary resistance unit R will, in the first instance, serve to control or govern the amperage to the arc lamp A through the circuit connections, including the solenoid B. It frequently happens, however, that after the maximum amperage 85 which it is safe and advisable to pass through the solenoid has been supplied through the primary resistance unit R, it is desirable to supply additional amperage 90 to the carbons of the lamp, and to accomplish this result, the secondary or shunt resistance unit R' is brought into operation, 95 which permits additional current to pass from the positive pole or same side of the power connection, on through the secondary 100 coil s of the resistance unit R' direct to the carbons of the arc lamp without passing through the solenoid. The present arrangement readily makes this possible, as may be observed by tracing the path of the circuit 105 through the coils of the resistance units R and R', as follows:

From the switch arm 10 of the controller which is connected directly with the line wire terminal P, the current will pass 110 through the contact 11 and its connection 11^a to the secondary coil p of the primary resistance unit R. The connection between the button 11 and the primary coil p through the wire 11^a is such that the full 115 resistance of the primary resistance coil is thrown into the line which includes the coil and its connection p' to the terminal 6. From this terminal the current is led by the connection p² to the solenoid B of the arc 120 lamp and thence through the connection p³ to the carbon of the lamp. If more amperage is desired the switch arm 10 may be shifted to the button 12, when the section of the primary coil p between the connections 125 11^a and 12^a will be cut out in the well-known manner, and likewise as more amperage is desired the switch arm 10 may be moved to successive buttons 12, 13, 14 and 15, each time cutting out more resistance until only the 130

pre-determined resistance of the coil p remains in the circuit with the arc lamp through the solenoid B.

During the full movement of the switch 5 arm 10 over the contacts 11 to 15, inclusive, the opposite end of the arm slidably contacts with the dead segment 11', but when the contact arm 10 engages with the contact segment 16 of the primary resistance unit 10 R, the opposite end of the arm will contact with the button 12' of the secondary resistance unit R'. Thus, the current will divide at the contact arm 10 and part will pass through the full length of the secondary 15 winding s while the remainder is passing through the shortened or predetermined portion of the coil p of the primary resistance unit R. Upon further movement of the switch arm over the segment 16 whereby 20 its opposite end may successively span the distance between the contact buttons 13', 14', 15' and 16' while still in engagement with the segment 16, a greater amount of amperage will be permitted to pass through 25 the secondary resistance unit R' through the cutting out of additional resistance in the coil s , whereby more amperage will flow through the connections s' which leads to the terminal member 7 of the rheostat. This 30 terminal is connected by the wire s^2 directly to a carbon of the arc lamp, through the wire p^3 , for instance, as shown in Figure 6. In this way additional amperage is supplied to the carbons of the arc lamp without 35 passing through the solenoid B, consequently imposing a greater amperage on the carbons than could be distributed with the desired margin of safety and maximum efficiency through a single resistance unit and 40 a solenoid.

In its primary aspect, therefore, the present invention proposes to provide a pair of resistance units which may be selectively included in series with a translating device 45 having a control element, such for instance as the solenoid B bears to the carbons of the arc lamp A, whereby a maximum amperage capacity may be supplied from the power line to the translating device through its 50 control element, while at the same time when a greater amperage capacity is desired for the translating device, such ampere capacity may be available through a shunt circuit directly between one of the terminals of the 55 power line and one of the carbons of the arc lamp, suitable resistance elements being interposed in said line, if desired and as shown, to thereby insure the safety of the apparatus, and to permit the solenoid control 60 of the arc to operate at maximum efficiency.

Without further description it is thought that the features and advantages of the invention will be readily apparent and it will, 65 of course, be understood that changes in the

form, proportion and details of construction may be resorted to without departing from the spirit of the invention or scope of the appended claims.

I claim:

1. A rheostat including primary and secondary resistance units, connections for placing the primary resistance unit in circuit with a source of power and a translating device, shunt connections for connecting the secondary resistance unit also with the translating device, and a controller having means for progressively increasing the ampere capacity of the primary resistance unit and also for progressively increasing the ampere capacity of the secondary unit, after the predetermined maximum capacity of the primary unit has been reached. 70

2. A rheostat including primary and secondary resistance units, connections for placing the primary resistance unit in circuit with a source of power and a translating device, shunt connections for connecting the secondary resistance unit also with the translating device, and a controller having means for progressively increasing the ampere capacity of the primary resistance unit, and also for connecting the secondary resistance unit, and progressively increasing the ampere capacity thereof, after the predetermined maximum capacity of the primary unit has been reached. 85

3. A rheostat including primary and secondary resistance units in combination with a translating device having a control element, a power connection with one terminal of the translating device, a main circuit connected with one of the terminals of the power line and including the primary resistance unit of the rheostat and the control 100 element for the translating device and electrically connected with the other terminal of said device, and a shunt circuit including the secondary resistance unit and electrically connected directly with one of the 110 terminals of the translating device and with one of the terminals of the power line. 105

4. A rheostat including primary and secondary resistance units, a controller, power terminals in combination with a translating 115 device having an electrical control unit, an electrical connection directly between one of the power terminals and the translating device, a circuit including the other power terminal, the coil of the primary resistance 120 unit and the control unit of the translating device in series with the said translating device, a shunt circuit, closed by the controller from the main circuit, through the coil of the secondary resistance unit, and an 125 electrical connection directly between the coil of the secondary resistance unit and the translating device.

5. A rheostat comprising a casing having a switch board at one end and a terminal 130

board at the other end, a step by step controller switch carried by the switch board, a plurality of binding terminals carried by the terminal board, a removable frame with in the casing, separate primary and secondary resistance units mounted within the frame, wire connections between the controller contacts and both resistance units at a plurality of points.

10 6. A rheostat including a frame, oppositely arranged pairs of insulating supporting spools, a separate resistance element associated with each pair of spools and consisting of a single length of wire formed 15 into two coils respectively carried upon the separate spools of the said pair, and means for closing the circuit through the second resistance element at the point where the maximum capacity of the first resistance 20 element is reached.

7. A rheostat including primary and secondary resistance units, connections for placing the primary resistance unit in circuit with the positive or a single pole of the 25 source of power and a translating device; connections for placing the secondary resistance unit in circuit with the same pole of the same source of power and translating device; and a controller having means for

progressively increasing the ampere capacity 30 of the primary resistance unit, and also for progressively increasing the ampere capacity of the secondary unit after the predetermined maximum capacity of the primary 35 unit has been reached.

8. A rheostat including primary and secondary resistance units, connections for placing the primary resistance unit in circuit with the positive or a single pole of the source of power and a translating device; 40 connections for placing the secondary resistance unit in circuit with the same pole of the same source of power and translating device; and a controller having means for progressively increasing the ampere capacity 45 of the primary resistance unit, and also for connecting the secondary resistance unit, and progressively increasing the ampere capacity thereof, after the predetermined maximum capacity of the primary 50 unit has been reached.

In testimony whereof I hereunto affix my signature in the presence of two witnesses.

EARL G. PERKINS.
